COMBINED SOAP TRAY AND TOY RECEPTACLE

Richard Bohan, 88 Edgewood Place,
Edgewater, N.J. 07020

Filed Aug. 17, 1970, Ser. No. 24,512

Term of patent 14 years

Int. Cl. D6—99

U.S. Cl. D33—24

FIG. 1.

FIG. 2.

FIG. 4.

FIG. 3.

FIG. 5.

FIG. 1 is a top and front isometric view of the combined soap tray and toy receptacle, embodying the features of my new design,

FIG. 2 is a top plan view,

FIG. 3 is a side elevational view,

FIG. 4 is a rear elevational view, and

FIG. 5 is a bottom plan view thereof.

I claim:

The ornamental design for a combined soap tray and toy receptacle, substantially as shown.
